LINE GUIDE FOR FISHING RODS

Edward J. Golec, Chicago, Ill., assignor to Sears, Roebuck and Co., Chicago, Ill., a corporation of New York

Original design application July 5, 1963, Ser. No. 75,684.
Divided and this application Nov. 20, 1964, Ser. No.
82,711

Term of patent 14 years

(Cl. D31—4)

Fig. 1.

Fig. 2.

FIG. 1 is a front elevation of a line guide for fishing rods showing my new design, the rear being a mirror image of the disclosed front portion; and

FIG. 2 is a side elevation thereof, the opposite side is a mirror image of the side shown.

This application is a division of my co-pending application, Serial No. D. 75,684, filed July 5, 1963.

I claim:

The ornamental design for a line guide for fishing rods, substantially as shown.
